UNITED STATES PATENT OFFICE.

EDMUND F. HOSKIN, OF EVANSTON, ILLINOIS, ASSIGNOR TO THE HOSKINS COMPANY, OF CHICAGO, ILLINOIS, A CORPORATION OF ILLINOIS.

ELECTRIC HEATER.

No. 877,843.

Specification of Letters Patent.

Patented Jan. 28, 1908.

Application filed September 19, 1907. Serial No. 393,729.

To all whom it may concern:

Be it known that I, EDMUND F. HOSKIN, a citizen of the United States, residing at Evanston, in the county of Cook and State of Illinois, have invented a new and useful Improvement in Electric Heaters, of which the following is a specification.

My invention relates to an improved construction of electric heater and is intended 10 for embodiment in various forms to adapt it for application to different purposes, as for heating sad-irons, for heating water by immersion therein of the heater, and for use as a soldering "iron", in which last-named 15 form of embodiment it is illustrated in the accompanying drawings.

Referring to the drawings, the first six views illustrate the successive steps employed in constructing one form of soldering iron 20 in accordance with my invention, Figure 1 showing a section of the spiral resistance-wire used, Fig. 2, a longitudinal section of the insulating tubing or covering in which the wire is incased, Fig. 3, a similar view of 25 the spiral wire in the insulating tube, Fig. 4, a similar view of the metal handle-tube about which the insulated spiral section of the resistance-wire is coiled and through which its straight terminal-ends are passed, Fig. 5, 30 a view in elevation of the handle-tube with the aforesaid insulated resistance-wire upon it, and Fig. 6, a view in sectional elevation showing the device of Fig. 5 in a mold in which copper is cast about the insulated coil 35 on the tube to form the heat-transmitting element, or head, of the implement. Fig. 7 is a broken view in sectional elevation of the implement as it appears when removed from the mold, and Fig. 8 shows the finished soldering-iron by a view in elevation. Fig. 9 is 40 a view in sectional elevation showing a modified embodiment of the invention in a soldering iron and illustrating the method of constructing the modified device.

Referring particularly to Figs. 1 to 8, inclusive: The resistance-conductor 10 employed, which in the present instance is in wire-form and preferably that forming the subject of Letters Patent of the United States 50 No. 811,859, granted February 6, 1906, to A. L. Marsh for an electric-resistance element, is coiled into a spiral between its ends, the entire wire being covered by insulation, as by introducing it into a tube 11, preferably 55 of asbestos. This wire is inserted into a

metal tube 12 with the spiral section protruding beyond one end thereof, leaving a straight section to extend longitudinally through the tube and project beyond its opposite end to form a terminal; and the 60 spiral section of the wire is coiled about the exterior of the tube up to an opening 13 therein, into which the other straight section of the wire is inserted and passed through the tube to extend therein along the first-named 65 straight section.

The structure thus produced in the form represented in Fig. 5 is introduced into a suitable mold 14, which may be best composed of graphite with its chamber in the 70 form of a soldering-iron head 15, and being properly supported in the mold the metal (preferably copper) in molten condition is poured into it to form the head by casting. The result is represented in Fig. 7, and on 75 providing a heat-insulating handle 16 on the outer end of the tube 12 and extending through it the insulated end-sections of the wire 10 to form the leads for connection with a supply of electric current, the implement 80 is completed.

Among the advantages of the construction the following may be mentioned: By bringing the metal of the heat-transmitting element or head 15 into intimate close contact with 85 the insulated resistance-conductor, formation of air-spaces is prevented, which would incur loss of heat, while the absence of such air-spaces enables the minimum amount of current to quickly heat the transmitting 90 element sufficiently for its purpose; and the head effectively seals the resistance-conductor against access of air and other gases and water and therefore against their tendency to shunt the current and of oxidizing 95 the conductor with the effect of unduly increasing its resistance. As will be observed, the metal of the head, in casting it, flows between the turns of the coil in the wire 10, thereby bringing it into intimate contact 100 throughout with the metal to be heated. These same advantages are attained by the modified construction illustrated in Fig. 9, which differs mainly from the construction hereinbefore described in the matter of insulating the resistance-conductor 10, and is produced as follows: The inner end of the handle-tube 12 fits over a neck 17 extending from one end of a solid cylinder 18 of electro-insulating material, such as soapstone, hav- 110

ing a wire-passage 19 formed longitudinally through it and through the neck, and provided externally with a spiral groove 20 in which the naked resistance-wire 10 is wound, 5 one end being passed through the tube and through a wire-passage 21 in the neck and upper portion of the body of the cylinder 18 to be spirally wound about the latter, and the other end of the wire being run through 10 the passage 19 and tube to afford the leads. The wire-wound cylinder is introduced into a cup-like shell 22 of insulating material such as soapstone or talc, in which it fits closely, being secured therein by a cover 23 seating 15 in the open end of the cup about the tube 12 against the cylinder-end and secured in place, as by cementing it with silicate of soda or other suitable medium.

The head 15 is formed on this modified 20 structure in the same way as already described, namely by introducing the parts on the stem or tube 12 into a mold 14 and casting the metal about them, according to the representation in Fig. 9.

25 What I claim as new, and desire to secure by Letters Patent, is—

1. An electric heater comprising, in combination, a handle-stem a coiled insulated resistance-wire on said stem and having its 30 ends extended along the same forming terminals, and a metal heat-transmitting head cast about said wire in intimate contact with the insulation thereon.

2. An electric heater comprising, in combination, a tubular handle-stem, a coiled insulated resistance-wire on said stem and having its ends extended through the same forming terminals, and a metal heat-transmitting head cast about said stem and wire in intimate contact with the insulation thereon. 35

3. An electric heater comprising, in combination, a handle-stem, a body of insulating material connected with said stem and having a resistance-wire coiled about it and a shell of insulating material in which said 45 wire-wound body is confined and hermetically sealed, terminals leading from said wire, and a metal heat-transmitting head formed about said shell.

4. An electric heater comprising, in combination, a tubular handle-stem, a body of insulating material having a neck about which said stem fits at one end and provided with an external spiral groove, an electric resistance-wire having terminal end-sections 55 extending through said stem and wound between said sections into said groove, a shell of insulating material in which said wire-wound body is confined, a cover hermetically sealed in the open end of said shell 30 about said neck, and a metal heat-transmitting head formed about said shell.

EDMUND F. HOSKIN.
